DESIGN FOR A SHOE OR SIMILAR ARTICLE

Oswald M. Pick, Chicago, Ill., assignor to The Florsheim Shoe Company, Chicago, Ill., a corporation of Illinois

Application December 5, 1940, Serial No. 97,083

Term of patent 3½ years

To all whom it may concern:

Be it known that I, Oswald M. Pick, a citizen of the United States and a resident of the city of Chicago, in the county of Cook and State of Illinois, have invented a new, original, and ornamental Design for a Shoe or Similar Article, of which the following is a specification, reference being had to the accompanying drawing, forming a part thereof.

On the drawing:

I claim:

The ornamental design for a shoe or similar article, as shown.
